(57) **CLAIM**

The ornamental design for a IV pole accessory, as shown and described.

DESCRIPTION

FIG. 1 is a perspective view of an ornamental design for a first embodiment of an IV pole accessory.

FIG. 2 is a front view thereof.

FIG. 3 is a rear view thereof.

FIG. 4 is a first side view thereof.

FIG. 5 is a second side view thereof.

FIG. 6 is a top view thereof; and,

FIG. 7 is a bottom view thereof.

The broken lines shown in FIGS. 1-7 are included for the purpose of illustrating environmental elements only and form no part of the claimed design.
